[57] CLAIM

The ornamental design for a numbering machine, as shown and described.

DESCRIPTION

FIG. 1 is a top, front, and left side perspective view of a numbering machine showing my new design;

FIG. 2 is a top plan view thereof;

FIG. 3 is a front elevational view thereof;

FIG. 4 is a right side elevational view thereof, the left side being a mirror image of the right side shown;

FIG. 5 is a rear elevational view thereof; and

FIG. 6 is a bottom plan view thereof.

FIG-1

FIG-2

FIG-3

FIG-4

FIG-5

FIG-6
